APPARATUS FOR RECOVERING PLACER GOLD

Walter C. Hanson, Hillsboro, N. Mex., assignor, by
mesne assignments, to Natural Resource Development Company, Dallas, Tex.

Application November 5, 1934, Serial No. 751,497

9 Claims. (Cl. 209—12)

This invention relates to the recovery and saving of gold from near surface deposits or what are more commonly termed placer deposits and the like, and it has to do with a novel apparatus for economically and profitably saving, more particularly, the fine or flour gold contained in placer or so-called low grade deposits.

The great problem has been to recover the gold from these deposits at a profit and for years

efforts have been made for such accomplishment with but little success. Many improvements have been made in the mining, transportation, crushing and recovery of gold from the low grade ore found in the quartz or lode mines, and many such mines that were unprofitable by the old methods are, with the improvements, now workable on a well-paying basis. However, small indeed are the improvements that have heretofore been made in the recovery and saving of the fine or flour gold from low grade placer deposits. The present invention, therefore, has been brought about to secure a relatively high saving of the fine or flour gold and at a greatly minimized cost for machinery and operating expense.

In the preliminary handling of the material to be treated, the material is taken from the deposit in placer mining by surface digging and shoveling and afterwards it is carried through stages of initial grading, scouring and washing, and then concentration for final recovery and saving of the gold for amalgamating, retorting and forming it into bars. The methods heretofore employed, as hereinbefore stated, have involved but little improvement and the apparatus used not only has been produced at relatively high cost but cost of operation has been also high and the percentage of gold recovered so small that the process of recovery has, in most cases, been unprofitable and so much so that the operators have ceased operating.

One reason for failure, or at least, unprofitable operation with the processes heretofore followed, is the character of the material, particularly where the clay or caliche formation is encountered, as it most invariably occurs in the vast areas, particularly in the placer deposit regions of southwestern United States and Mexico, and even extending to South America. However, by the term "caliche", as hereinafter used, more particularly, is meant a calcareous sedimentary deposit, locally named in Arizona. It is the compacted residual or alluvial surface deposit, cemented by infiltrated calcareous material, found over extensive areas in the semi-arid regions of Mexico and southwestern United States. This

material is known to contain much fine or flour gold, but due to its characteristic plasticity and tenacity when wet, great difficulty is experienced in extracting the gold therefrom. The present invention, therefore, has for one of its main objects to overcome the natural suction and tenacity of this material in its watered condition, whereby to effect quickly and inexpensively the recovery of the fine gold therefrom.

The present invention consists in the method as hereinafter described with particularity and in the apparatus by which the method is carried into effect, and each also as set forth in the appended claims.

In the accompanying drawings, forming part 15 of this specification, and illustrating more or less conventionally in general, but with detail as to certain elements thereof, an apparatus for practicing the method of the invention,—

Figure 1 is a side elevation of the apparatus; 20

Figure 2 is a section on the line 2—2, of Figure 1;

Figure 3 is a detail view of the grizzly or initial screening device, detached from the apparatus;

Figure 4 is a top plan view of one of the concentrating tables; 25

Figure 5 is a longitudinal section on the line 5—5, of Figure 4;

Figure 6 is an inverted or bottom view of the concentrating table; 30

Figure 7 is a fragmentary view, in top plan, showing the discharge end portions of the several concentrating tables in cooperative relation to the conveyor trough;

Figure 8 is fragmentary sectional view on the line 8—8, of Figure 7; and

Figure 9 is a section transversely of a concentrating table, taken on the line 9—9, of Figure 5.

The apparatus as illustrated in the drawings 40 will now be described. Referring now more particularly to Figure 1, the numeral 1 designates an ordinary scoop-shovel or drag-line-bucket by which the material from the deposit is taken to the apparatus. As shown, this shovel or bucket 45 is in elevated position, ready to dump its contents onto a grading device 2, which is set at an angle of approximately forty-five degrees, and, as best illustrated in Figure 3, comprises a frame including end cross-members 3 and spaced bars 4. The 50 bars of the device 2 are spaced a considerable distance apart, so that relatively large pieces of material will pass therebetween, while the over-size pieces or boulders are shunted into a chute 5 and discharged from the chute back into 55

the pit from which the material is taken, or, obviously, in some cases, into a special pit or place of reception.

The material passing between the bars 4 of the 5 grizzly or grading device 2, falls into a hopper 6 in which reciprocates a scrubber device or grate-like frame 7, above which is located a water-discharging-nozzle 8 at the end of a water supply pipe 9 having a suitable controlling valve 10.

10 The washed material and washing water passes through the scrubber device 7 and from the bottom of the hopper 6, through an outlet tube 11, and thence into a further washing and screening device 12, termed a "trummel". This device, as shown, comprises a cylindrical outer shell 15 or casing, set at an incline downwardly towards its discharge end, and having rotatable axially therein a cylindrical screen 13 of comparatively fine mesh with respect to the outlet openings 20 through which the larger particled material is removed from the apparatus at the different stages of the treatment.

In the center of the screen 13 is a tubular core member 14, which is apertured throughout, as 25 at 15, and said screen and tubular core member are fixed to rotate together, the core member being journaled rotatably, but with leak-tight effect in any approved manner, in the end walls 16 which close the outer cylindrical shell 30 or casing 12; the outlet tube 11 from the hopper 6 discharging directly into the upper or higher positioned end portion of the tubular core member 14.

Material too large to pass through the apertures 15 in the tubular core member 14, are discharged through the core-outlet or mouth 16, onto a chute 17, whence the material so discharged is taken away by any suitable means for such treatment as may be desired. Material 40 passing through the apertures 15 of the tubular core member 14 is carried around in the surrounding screen 13 until finally disintegrated sufficiently to pass through the meshes of the screen, whereupon it is deposited in the longitudinally elongated hopper bottom portion 18 of the cylindrical outer shell or casing 12, at the middle of which is a well or receiving chamber 19.

From the bottom of the well or receiving chamber 19, are a series of discharge pipes 20 leading to positions above the upper or higher positioned end portions of concentrating tables 21, of which there may be one or more in the apparatus, but, as shown, there being six of such tables, each of which is identical in construction and operation. Therefore, only one will be referred to in describing the structure and peculiar operation thereof.

The concentrating table 21 comprises a rectangular, box-like body, having two side and one end wall. In practice the table is set normally at an incline downwardly to its open or discharge end. It is swingably supported by cables 22 at its four corner portions. These cables are relatively short, so that when endwise movement is imparted to the table it is reciprocated or oscillated thereon, with an arcuate up and down movement during its longitudinal reciprocation. This gives an operative effect to be presently more fully explained, which is an important feature of the invention.

The endwise movement of the table may be accomplished through any suitable or approved instrumentality. As shown, a yoke or Y-shaped 75 element 23 is hingedly attached, as at 24, to the

under side of the bottom of the table 21, and at its stem end portion it is swivelled or attached, by a ball-and-socket or other suitable universal joint, 25, to one end of a connecting rod or pitman 26, said rod or pitman being attached at its opposite end to an eccentric 27 by which it is reciprocated and oscillated, and, in turn, effects the reciprocation and oscillation of the table 21, as hereinbefore described. The eccentric 27, of which there is, of course, one for each table, as 10 shown, is mounted on a shaft 28 journaled in bearings 29 provided therefor on the side member 30 of the base or under-frame of the apparatus, there being one of these shafts on each side of the frame.

15 The shaft 28 is rotated by sprocket chain gearing 31 from a suitable motor, obviously electrical or of the internal combustion type, as may be most convenient in the locality where the apparatus is operated, and, preferably, as 20 shown, said motor, designated by the numeral 32, drives a counter-shaft 33 on the upper portion of the base or under-frame. On this counter-shaft 33 is fixed a toothed gear 34 which meshes with another gear 35 on the inner end 25 portion of the core tube 14 of the trummel 12, whereby rotation is imparted to said core tube simultaneously with the actuation of the concentrating tables 21. The shaft 33 is also provided with a miter gear 36 which drives a similar 30 gear 37 having a sprocket gear connection 38 with an eccentric 39, said eccentric 39 having a rod or pitman 40 hingedly attached, as at 41, to the initial scrubber device 7, whereby to reciprocate the latter, also simultaneously with the actuation 35 of the trummel and the concentrating tables.

In a box-like concentrating tables 21 mats or carpets 42 of strong, woven, felted or other suitable material of sufficient porosity or absorbent quality that fine or flour gold will work its way 40 into it, are placed in an undulated or corrugated form and arrangement, with looseness in the alternate rises thereof, which portions have placed thereunder transverse cleats 43 or supporting ribs (see Figure 5 of the drawings) which may rest loosely on the bottom of the table or, in some cases, where desirable, they may be fastened to the bottom of the table. At the alternate depressions in the mat or carpet 42 transverse riffles or baffles 44 are located. These riffles or baffles 50 44, as shown, are preferably formed integrally with longitudinal side members 45 of a removable frame which is readily placed in and taken from the box-like table 21, at will, or they may obviously be each separate one from another and placed 55 in and taken from the table individually.

The riffles or baffles 44 are of inverted L-shape, and the flange portions 46, at the upper edges thereof are disposed forwardly in the direction of flow and discharge of the watered material 60 delivered into the upper end portions of the downwardly inclined tables 21, as illustrated in the drawings. It is the forward disposition of these flanges 46 of the riffles or baffles 44, together with the reciprocatory and oscillatory motion imparted to the tables 21 and a pulsating action of the raised portions of the mat or carpet between the riffles or baffles, which gives the highly efficient action to secure a recovery of the fine gold in the material passing upon and through the tables 70 21. That is to say, the peculiar backward and forward movement of the tables longitudinally thereof, together with the simultaneous arcuate up and down movement thereof, causes the water-laden material to be rotated or eddied about a 75 80

transverse horizontal axis between each of the riffles or baffles 44, the forward disposition of the flanges 46 of the elements 44 causing a rolling movement of the material, as indicated by the arrows 47 and looped broken lines 48 in Figure 5 of the drawings. The carpet 42 is also pulsated between the riffles or baffles, thereby creating a counteracting, alternating vacuum or pulling suction and pushing effect upon the particles of the material in the body of water carrying it through the tables from the trummel 12, thereby not only tending to overcome the natural suction of the gold-contained caliche or clay-like material in its plastic and tenacious state, as it is when passing through the tables, but further having the effect of breaking up and disintegrating the material. Hence, the fine or flour gold is pocketed in the lower corners, in front of the respective riffles or baffles 44, to the rear of the rises 49 of the mat or carpet, as indicated by the stippling 50 in Figure 5 of the drawings, the larger particles of the material moving, with the rolling motion as indicated by the arrows 47 and broken lines 48, as it passes successively over the respective riffles or baffles 44, as herein just above described; it being, of course, understood that the watered material is delivered to the tables 21 near their upper or higher positioned receiving end portions.

The fine or flour gold obviously works into the porous or absorbent material of the mat or carpet, which from time to time is removed from the table and the gold absorbed or worked therein is extracted therefrom in any suitable or approved manner. To remove the mat or carpet it is only necessary to lift out the riffle or baffle frame first from the table, and after removal of the frame and mat or carpet the interior of the table may be readily cleaned. In this connection, it may be here noted that with the peculiar form and arrangement of the mat or carpet and the particular shape and disposition of the riffles or baffles, the fine or flour gold is recovered with relative rapidity from the material passed through the apparatus, and with a very high percentage of saving; and, not only that, the tables may be continuously operated for a much longer time than can the heretofore used concentrating tables of which the inventor of the present method and apparatus is aware,—that is to say, the old tables have to be cleaned every hour or two, whereas, the tables of the present invention can operate continuously for approximately twenty hours before cleansing is necessary or desirable. This, in itself, is a distinct economical advantage, in addition to the high efficiency in the process of recovery of the gold, not only that which is washed loose from the sand or particles of hard rock, but, as herein particularly described, the fine or flour gold is taken in exceptionally high percentage from the caliche or clay-like substance.

The residue, tailings, or waste from the several concentrating tables or jigs, as they may be termed, 21, is discharged into a trough or conveyor 51, from which it may be returned to the pit or source from which it was originally taken or to any other desired place or device for re-treatment. In this connection it may be here stated, that in some instances, the concentrates and metal taken from the concentrating tables or jigs 21 when cleaning them, and also the absorbed gold and material that is extracted from the carpet or mat 42 when it is removed from the table or jig, are run through a smaller table or jig of similar construction, arrangement and operation as the tables or jigs 21, before the final

panning of the concentrates which is done by experts in that art, prior to the amalgamating, retorting and forming the recovered gold into the usual bricks.

An important advantage in the use of the peculiarly constructed, arranged and operated concentrating table or jig of the present invention is that only a relatively small quantity of water is required for the operation of the tables or jigs in the concentrating process thereof, whereas, by the use of the old style devices a very large quantity of water was necessary, because of the plasticity of the caliche or clay-like substance and the natural strong suction or retentive tendency thereof which makes it very difficult, and, in fact, quite impossible with the heretofore used devices to extract but a very small percentage of the fine or flour gold from the substance, hence the necessity for using a relatively large quantity of water in order to lessen the degree of plasticity of the base substance, or, in other words, to make the substance more nearly fluid or liquid. By the peculiar construction and arrangement of the tables or jigs 21 of the present invention, the caliche or clay-like substance is effectively broken up or disintegrated to a larger degree than is possible in the old type of table or jig, and, furthermore, the rolling motion imparted to the stream of water embodied material passing through the concentrating device by the peculiar and novel disposition of the flanges 46 of the riffles 44, augmented by the alternating pulling suction and pushing of the pulsating carpet or mat 42, overcomes the natural retentive suction of the plastic material, whereby, as hereinbefore pointed out, an exceedingly high percentage of the gold is quickly recovered and, too, the tables may be operated continuously for a much longer time than the heretofore used tables before it becomes necessary to cleanse them.

The steps of the process of the present invention may be generally described as initially grading and washing the material as taken from the deposit, and passing the graded and washed material in a body of the washing water or liquid through a concentrating table or jig and subjecting the material, while so passing, to the pulsating action of a bottom carpet or mat and between riffles or baffles having forwardly projecting upper flange portions or means for creating a rolling motion of the watered or liquid embodied material from one riffle or baffle to the next riffle or baffle ahead, downwardly behind that riffle or baffle, thence rearwardly towards the bottom of the table or jig and upwardly and forwardly from the rearward riffle or baffle, and successively thus over the forward riffles or baffles to the discharge end of the table or jig.

Obviously, the apparatus for carrying the method or process into effect may be varied in many respects as to construction and arrangement, within the spirit and scope of the invention as herein set forth and claimed, and, therefore, the invention is not limited to the specific construction and arrangement of apparatus shown in the accompanying drawings.

What is claimed is:

1. A concentrating device, for the purposes described, comprising a reciprocatory table, a mat located in the lower portion of the table and provided with spaced supporting means to hold it in an undulated or corrugated formation, and baffles extending transversely of the table and located above the respective depressed portions of the mat and in substantial engagement therewith, 75

the rises of the mat between the respective baffles being sufficiently loose to pulsate with the reciprocation of the table.

5 2. A concentrating device for the purposes described, comprising a reciprocatory table, a mat located on the table and provided with spaced supporting means to hold it in an undulated or corrugated formation, and baffles extending across the table and located above the respective depressed portions of the mat and in substantial engagement therewith, the rises of the mat between the respective baffles being sufficiently loose to pulsate with the reciprocation of the table.

10 15 3. A concentrating device for the recovery of gold and the like from finely divided material containing the same, comprising a box-like reciprocatory table, a mat located in the lower portion of the table, and provided with spaced supporting means to hold it in an undulated or corrugated formation, and baffles extending transversely across the table and located above the respective depressed portions of the mat and in substantial engagement therewith, the rises of the mat between the respective baffles being sufficiently loose to pulsate with the reciprocation of the table.

15 20 30 35 40 4. A concentrating device for the recovery of gold and the like from finely divided material containing the same, comprising an inclined reciprocatory table, a mat located in the lower portion of the table, and provided with spaced supporting means to hold it in an undulated or corrugated formation, and baffles extending transversely across the table and located above the respective depressed portions of the mat and in substantial engagement therewith, the rises of the mat between the respective baffles being sufficiently loose to pulsate with the reciprocation of the table.

45 5. A concentrating device for the recovery of gold and the like from finely divided material containing the same, comprising an inclined reciprocatory table, a mat located in the lower portion of the table, and provided with spaced supporting means to hold it in an undulated or corrugated formation, and baffles extending transversely across the table and located above the respective depressed portions of the mat and in substantial engagement therewith, the rises of the mat between the respective baffles being sufficiently loose to pulsate with the reciprocation of the table, said baffles having flanges at their upper portions extending in the direction of downward inclination of the table.

55 6. In an apparatus for recovering gold from placer deposits and the like, a concentrating device comprising a downwardly inclined, longitudinally reciprocable table having side walls and one end wall, the open end being lowermost, an undulatingly arranged mat at the bottom of said table provided with spaced supporting means to hold it, and transverse baffles extending from side wall to side wall of the table and being re-

spectively disposed across the mat in the depressions between the rises thereof and in substantial engagement therewith, said baffles having forwardly extending flanges at their upper portions and the mat being sufficiently loose between the respective baffles to pulsate with the reciprocation of the table.

5 10 15 20 25 7. An apparatus for recovering gold and similarly heavy precious metal from material taken from placed deposits and the like, comprising means for initially grading, washing and scrubbing the material, means for screening and disintegrating the washed material in a body of the washing material, and a concentrating device arranged to receive the water embodied material from said screening and disintegrating means, said concentrating apparatus comprising an inclined reciprocatory table, a mat located in the lower portion of the table, and provided with spaced supporting means to hold it in an undulated or corrugated formation, and baffles extending transversely across the table and located above the respective depressed portions of the mat and in substantial engagement therewith, the rises of the mat between the respective baffles being sufficiently loose to pulsate with the reciprocation of the table.

30 35 40 45 50 55 8. An apparatus for recovering gold and similarly heavy precious metal from material taken from placer deposits and the like, comprising means for initially grading, washing and scrubbing the material, means for screening and disintegrating the washed material in a body of the washing material, and a concentrating device arranged to receive the water embodied material from said screening and disintegrating means, said concentrating apparatus comprising an inclined reciprocatory table, a mat located in the lower portion of the table, and provided with spaced supporting means to hold it in an undulated or corrugated formation, and baffles extending transversely across the table and located above the respective depressed portions of the mat and in substantial engagement therewith, the rises of the mat between the respective baffles being sufficiently loose to pulsate with the reciprocation of the table, said baffles having flanges at their upper portions extending in the direction of downward inclination of the table.

50 55 60 65 70 75 9. In combination, a reciprocatory concentrating table with a generally flat top, a canvas covering therefor, means to reciprocate the table, means on the table to support the canvas so as to form a series of alternately positioned transversely extending rises and depressions, the depressed portions of the canvas resting on the table, and the supporting means arranged to support the side portions of the rises so as to be free to flex upwardly and downwardly slightly during reciprocation of the concentrating table, and transversely extending bars positioned over the depressions and having their lower edges adjacent the top of the canvas.

WALTER C. HANSON.
